TETRAHYDROPHthalic ALKYD RESINS

Alexander C. Keyl, Bensenville, and Robert H. Geils, Downers Grove, Ill., assignors to Fred K. A. Stresen-Reuter, Inc., a corporation of Illinois

No Drawing. Application September 27, 1950,
Serial No. 187,129

9 Claims. (Cl. 260—22)

1 This invention relates to tetrahydrophthalic alkyls and more particularly to improved oil modified alkyl resins derived from tetrahydrophthalic acid and to methods of producing the same.

In our copending application Serial No. 187,130 filed of even date herewith, we have disclosed the production of a tetrahydrophthalic acid half ester intermediate of a mono fatty ester of a polyhydroxy aliphatic alcohol having the following 10 formula:

or the isomeric structure wherein some of the half ester is upon a different hydroxyl:

wherein R is the alkyl, alkenyl, or hydroxy alkenyl typical long chain residue of saturated or unsaturated fatty acids including drying oil fatty acids, generally derivable by hydrolysis or saponification of commercial animal, fish and vegetable oils and fats. Such fatty acids may contain 10 to 22 carbon atoms and preferably 17 to 22 carbon atoms; R' is hydrogen or a lower alkyl group, having 1 to 3 carbon atoms which may additionally be substituted with up to three hydroxyl groups distributed not more than one hydroxyl group for each carbon atom; R'' is hydrogen or a monocarbocyclic 5 or 6 carbon atom ring radical, which may further contain lower alkyl substituents, such as phenyl, toluyl, cyclohexyl, methyl cyclopentyl, or an alkyl radical having 1 to 16 (or an alkenyl radical having 2 to 16) carbon atoms such as methyl, ethyl, ethylene, propyl, propenyl, butyl, isobutyl, di iso-butyl,

n-octyl, decyl, decenyl, dodecyl, oleyl and hexadecyl; and X is hydrogen or halogen such as chlorine or bromine.

2 This intermediate is a viscous liquid stable at normal temperatures and which may be self condensed to an alkyl type resin, since it contains a free carboxyl radical and one or more free hydroxyl radicals. This intermediate also may have drying properties when the fatty acid with which it is esterified is derived from a drying oil fatty acid.

As indicated, the oil modified alkyl resin produced from such intermediate has an average aliphatic chain length of 10 to 22 carbon atoms 15 which serves to classify resins produced therefrom as of medium oil length, i. e. the quantity and type of oil (fatty acid) used to modify the resin. Thus a resin with a substantially large ratio of fatty acid to the rest of the molecule, 20 termed a "long oil" resin, has the desirable property of producing highly flexible soft and ductile films, when such resin is used in a coating composition. A resin having a small quantity of ratio of fatty acid to the rest of the molecule is termed 25 a "short oil" resin, a type characterized by being a harder resin capable of producing hard films and having substantial resistance to water, acids or alkalies.

In general, oil length of a resin, for purposes 30 herein, may be quantitatively classified as:

	Fatty acid per cent
Short oil alkyl	45-50
Medium oil alkyl	50-60
Long oil alkyl	60-75

35 wherein the percentages are weight percent of fatty acid with respect to total resin.

According to the present invention we have found that the tetrahydrophthalic acid half ester intermediate is amenable not only to easy resinification as such to the medium oil modified alkyl resin, but may be further modified to produce long oil resins as desired in a direct resinification of this intermediate with more fatty acids of the same or different type of that already present in the intermediate.

We have further found that a short oil resin 45 may be directly produced by reaction of the intermediate with a polyhydric alcohol which tends 50 merely to lower the ratio of fatty oil to the rest of the molecule in a direct resinification of the intermediate.

Finally, we have further found that the oil length may be shortened and the resin simultaneously modified as to the alkyl type of reac-

3

tion of the intermediate with mono or polybasic organic acids to introduce, as a monobasic acid, a resin type of acid such as pimamic, naphthenic, abietic or other mono acids of a resinous or resin forming type including such resin acids which may have been hydrogenated, of which the resin acids are preferred, but other typical dibasic organic acids of the character of phthalic acid, maleic acid, succinic acid, citric acid, adipic acid, sebasic acid or their anhydrides normally used in alkyd resin formation may be used for further modification of the intermediate to produce short oil alkyls.

Thus, it is the primary object of the present invention to resinify a tetrahydrophthalic acid half ester intermediate of a fatty acid ester of a polyhydric aliphatic alcohol as defined above to form resins of the alkyd type of controlled oil length. Other objects will be inherent in the description hereof.

For modifying the intermediate according to the present invention, it is reacted in proportions which may vary rather widely such as from equal proportions of intermediate and modifying component to from 3 mols of intermediate to 0.1 mol of modifier, but preferably in the range of 3 mols of modifier to from 1 to $\frac{1}{4}$ of a mol of the modifying component, the modifying component being of the character listed above such as a polyhydric alcohol, or a mono or dibasic organic acid of which the monobasic acid may be a resin acid or fatty acid. The reaction, in general, of the intermediate with one of these modifying agents is effected by mixing the intermediate with the modifier preferably by dissolving both reagents in a solvent capable of azeotropic distillation, such as an aromatic or aliphatic naphtha, preferably toluene, xylene or a coal tar or petroleum oil distillate of aromatic or aliphatic character, boiling in the range of 150 to 400° F. The solution is then azeotropically distilled at the temperature of azeotropic distillation over a period of 5 to 20 hours, continuously separating the water of condensation from the distillate and continuously recycling the solvent to the still as the condensation proceeds.

It is possible to effect reaction of the intermediate with the modifying agent to produce simultaneously therefrom a modified resin by directly heating the mixture in the same temperature range for an analogous period of time. However, this latter method is not preferred inasmuch as some decomposition may take place. Where the latter method is used it is preferable to effect the condensation by heating the mixture under a blanket of inert gas such as carbon dioxide or nitrogen.

The resinous condensate usually has an acid value of less than 50 and it may have an acid value of substantially zero where the condensation is carried to the end point. It will be understood that it is not essential to carry the condensation to the end point unless acid reacting pigments such as zinc oxide are to be mixed with the resin in forming a coating composition, in which event it is essential that the resin be substantially neutral.

1. Direct resinification of the half ester without modification

Intermediate   medium oil   water
half ester   heat   modified +
                    →   alkyd

The intermediate is dissolved in the solvent and 75 glyceride of soy bean oil fatty acid with maleic

azeotropically distilled by heating to the distillation point of the solvent and moisture of condensation. The condensate is collected outside of the still. The water distilled with the solvent is separated and the solvent is continuously returned to the still. The end point of resinification is determined when no more water comes over and the acid value has been reduced to less than 50. Alternatively, the azeotropic distillation may be effected by direct passage of steam into the resin solution in the volatile solvent. Alternatively direct resinification of the intermediate may be effected by heating the same without a solvent under an inert gas blanket of carbon dioxide. The resin formed in solution may be used directly or the solvent may finally be separated.

2. Reaction of the intermediate with a fatty acid to produce a long oil modified alkyd resin

The resin intermediate and fatty acid are dissolved in the solvent in proportion of 3 mols of intermediate to from 1 to $\frac{1}{4}$ of a mol of a fatty acid, which may be the same or different than the fatty acid already contained esterified in the intermediate. Where the resin is to be used as a coating composition, the fatty acid is preferably an unsaturated fatty acid derived from a drying oil such as linseed oil, tung oil or soy bean oil, but such as fish oil, lard, stearin, palm oil, peanut oil, coconut oil or castor oil. Both the intermediate and the fatty acid are dissolved in the hydrocarbon solvent to approximately a 50 to 80% solution and azeotropically distilled to remove water of condensation and form the oil modified alkyd resin of the long oil type having a high oil content such as from 60 to 75% of the resin.

3. Reaction of the intermediate with a polyhydric aliphatic alcohol to produce a short oil modified alkyd resin

The half ester intermediate is mixed with a polyhydric alcohol of the character of ethylene glycol, trimethylene glycol, diethylene glycol, propylene glycol, butylene glycol, glycerol, polyglycerol, mannitol, sorbitol, pentaerythritol or dipentaerythritol in proportion preferably of 3 mols of intermediate to from 1 to $\frac{1}{4}$ mols of polyhydric alcohol, and dissolved in a solvent capable of azeotropic distillation such as the hydrocarbon solvents mentioned above. The solution in 50 to 80% strength is azeotropically distilled over a period of 2 to 20 hours to produce a short oil type alkyd resin predominating in hydroxy groups. Resins of this type produce hard films.

4. Reaction of intermediate with monobasic resin acids to produce a resin-modified alkyd resin

The intermediate is mixed with a monobasic resin acid having at least one free carboxyl group such as rosin acids, naphthenic acids, or hydrogenated products thereof, in proportion preferably of 3 mols of intermediate to from 1 to $\frac{1}{4}$ mol of the resin acid, and reacted by distilling the solvent from the dissolved mixture of reagents in 50 to 80% solution over a period of 2 to 20 hours. The resin produced is a hard alkyd resin of short oil character. A similar procedure is used to produce a resin by modification of the intermediate with a dibasic acid.

EXAMPLE I

An intermediate as described in my co-pending application is prepared by first reacting the mono-

anhydride in equimolar proportions and heating the same under a blanket of inert gas at a temperature of 180° F. until an acid value of 122.70 was obtained. This product was then dissolved in xylene to form a 70% solution, mixed with liquid 1,3 butadiene in equimolar proportions and heated in an autoclave with stirring for 36 hours at a temperature of 115° F. and a pressure of 19 pounds per square inch. The product had an acid value of 105.4 and comprised the tetrahydrophthalic acid half ester of the mono soy bean fatty acid glyceride which is an oily fluid stable at room temperature.

The tetrahydrophthalic acid half ester was dissolved in xylene to form a 48% solution of non-volatile solids in xylene. The solution was placed in an ordinary still and fitted with a condenser from which the condensate could be separated into layers of solvent and water azeotropically distilled therewith, and the solvent layer recycled to the still. The distillation is carried out by continuous distillation at a temperature of approximately 334° F. to yield a solution of resin in xylene. The resin solution obtained after distilling for two hours had a viscosity of A-1 (Gardner-Holdt), color of 9-10 (Gardner) and an acid value of 12. To the solution of 48% non-volatile resinified solids in xylene, a drier comprising a mixture of a 0.5% lead naphthenate and 0.05% cobalt naphthenate based upon the non-volatile solids was added. The solution was then distributed as a film on glass and air dried. The film was found to have a slight tack to paper after six hours and was tack free to paper in 24 hours. The film was transparent and comprised the self polymerized intermediate of tetrahydrophthalic acid and soy bean oil fatty acid monoglyceride.

While as indicated the intermediate of this example is originally formed from soy bean oil fatty acid, the fatty acid may be obtained from various other sources where it is only slightly unsaturated or completely saturated such as from fish oil, lard, stearin, palm oil, peanut oil, coconut oil or castor oil, or the fatty acid may be of the drying oil type as obtained from such oils as linseed oil or tung oil. Similarly, while glycerides preferably form the base polyhydric alcohol of the intermediate, other polyhydric alcohols containing at least three hydroxyl groups may be used within the scope of the formula for the intermediate given above, for example, polyglycerol, mannitol, sorbitol or pentaerythritol which may be further substituted with lower alkyl groups. The tetrahydrophthalic acid may be formed from 1,3 dienes other than butadiene of this example such as 4-phenyl butadiene 1-3, 4-p tolyl butadiene 1-3, 4-cyclohexyl butadiene 1-3, 4-(2 methyl cyclo pentyl) butadiene 1-3, 1-chloro pentadiene 1-3, 4-isopropyl butadiene 1-3, hexadiene 1-3, di isobutyl butadiene 1-3, heptadiene 1-3, octadiene 1-3, 1-bromo pentadiene 1-3, 4 dodecyl butadiene 1-3, and octadecyl butadiene 1-3. Any of such intermediates may be substituted in this and other examples hereof as the intermediate.

EXAMPLE II

The intermediate as obtained in Example I is dissolved as a 70% solution in mineral spirits consisting of an aliphatic petroleum naphtha having a boiling point in the range of 150 to 400° F. together with rosin in the ratio of 3 mols of soy bean oil fatty acid monoglyceride half ester of tetrahydrophthalic acid to 1 mol of rosin containing about 90% of abietic acid and 10% pimaric acid, and azeotropically distilled at a tem-

perature of 370 to 380° F. with continuous separation of the water of condensation and recycling of the solvent for a period of 7 hours and 50 minutes. The condensation product is an oil and rosin modified alkyl resin and has the following physical characteristics.

Viscosity Q plus (Gardner-Holdt)

Color 12 plus (Gardner 1933)

Acid value 50.4 (determined on non-volatile matter)

Non-volatile matter 74%

The 74% solution of the resin obtained in this example was mixed with a standard drier consisting of 0.05% of cobalt metal and 0.5% lead metal based on the non-volatile matter content of the solution added as naphthenates. A 0.003" film of the solution was spread upon glass and was found to dry dust free after 5 hours and 15 minutes and set to touch after 6 hours and 40 minutes. The film showed a very slight tack to touch after 24 hours. A similar film on glass was placed in an air drying oven and baked at a temperature of 200° F. and set tack free in 3 hours.

EXAMPLE III

The soy bean fatty acid monoglyceride tetrahydrophthalic acid half ester intermediate of Example I was mixed in proportion of 74.2 grams of intermediate and 1.6 grams of Pentek, the latter comprising approximately 85% of pentaerythritol and 15% dipentaerythritol, the theoretical quantity necessary to produce a zero acid value for an intermediate containing one free carboxyl group. The two ingredients were mixed with petroleum mineral spirits having a boiling point range of 250 to 400° F. to form a 30% solution therein and distilled azeotropically at about 360° F. with continuous recycling of the condensed solvent after separation of water, over a period of 6 hours and 20 minutes. The resin solution obtained had a viscosity of V-W (Gardner-Holdt); color 10-11 (Gardner 1933), acid value 9.1, non-volatile matter content 48.1%. A similar ratio of driers as in Example II, comprising a mixture of cobalt and lead naphthenates was added to the solution and a 0.003" film was applied to glass. The film dried dust free after six hours and 40 minutes and set to touch after 8 hours and 20 minutes. After 24 hours the film showed a very slight tack to touch. A similar film baked in an air drying oven at a temperature of 200° F. was found to be tack free after six hours of baking time.

By way of comparison the intermediate alone condensed in a series of heating periods under the same conditions as in this example had acid values ranging from 20 to 35, indicating that condensations of intermediate with polyhydric alcohols lower the acid value and produce shorter oil length alkyls. In this example any of the polyhydric alcohols listed above may be substituted for the Pentek to produce resins of similar properties.

EXAMPLE IV

Three mols of the intermediate of Example I was reacted with 1/4 of a mol of linseed oil fatty acid by azeotropically distilling the mixture as a 75% solution in xylene at a temperature of 375° F. for a period of 5 hours and 45 minutes. The product had an acid value of 24 and was found to dry tack free on a 0.003" film of glass in 24 hours. In this example any fatty acid having from 10 to 22 carbon atoms may be substituted

7
for the linseed oil to produce long oil resins
hereof.

EXAMPLE V

The intermediate of Example I was mixed in proportion of 3 mols of intermediate with one mol of maleic anhydride and azeotropically distilled as a 75% solution in xylene over a period of 4 hours and 15 minutes. The product had an acid value of 45. It dried to a hard resinous coating in an air drying oven at a temperature of 200° F., and was tack free in 6 hours. In this example various dibasic acids and anhydrides thereof listed above may be substituted for the maleic anhydride.

As thus described valuable oil modified resins are prepared by further modification and resinification of an intermediate tetrahydrophthalic acid half ester of a mono fatty ester of a polyhydric alcohol by heating such an intermediate with an additional drying oil fatty acid, a polyhydric aliphatic alcohol, a monobasic resin acid or a polybasic organic acid preferably in an azeotropic distillation in a solvent to continuously remove water of condensation, for simultaneous esterification of these acids or alcohols with either a free hydroxyl radical or carboxyl radical contained in the intermediate, and simultaneous condensation of the modified product to an oil modified alkyd resin of readily controlled oil length, drying properties and widely variable properties of the resin per se.

As thus described the resins herein are subject to exact control of esterification of either a free carboxylic acid group or one or more free hydroxyl groups contained in a stable intermediate, with mono or polybasic organic carboxylic acids or with a polyhydric alcohol to produce an alkyd resin by a simultaneous esterification and condensation wherein all of the components are reacted to form a unitary resin compound as distinguished from unreacted mixtures. Thus exact control of the oil length for an oil modified alkyd resin is possible as well as the character of the resin itself, i. e. as to hardness or flexibility of film, the solubility thereof in various solvents, and the rate of drying or resistance to drying, as desired.

Various modifications of these alkyd type resins are possible as are known in the art of formation of alkyd resins. If desired the intermediate herein may be modified with various mixtures of monobasic and dibasic organic acids, including monobasic acids of either drying or non-drying fatty acids as well as rosin acids. Such acid mixtures may further be used with mixtures of additional polyhydric alcohol. The resinification may be effected in the presence of modifiers such as plasticizers and drying agents. The resins after formation may also be mixed with pigments, drying oils and other resins, etc., as are known in the resin and coating arts to form improved coating compositions of the oil modified resin type as well as resins for other uses.

It is accordingly intended that the examples given herein be regarded as illustrative and not limiting except as defined in the claims.

We claim:

1. The method of forming an alkyd resin comprising simultaneously esterifying and condensing an intermediate product, comprising a monomeric tetrahydrophthalic acid half ester of a monoester of a 10 to 22 carbon atom fatty acid with a polyhydric aliphatic alcohol having at least three hydroxyl groups, with an esterifying agent

5
agent selected from the group consisting of a 10 to 22 carbon atom fatty acid, a natural resin acid and hydrogenation products thereof, a polycarboxylic organic acid and anhydrides thereof and polyhydric aliphatic alcohols.

2. The method of forming an alkyd resin comprising simultaneously esterifying and condensing an intermediate product having the formula:

20
wherein R is selected from the group consisting of the alkyl and alkenyl radicals of a fatty acid having from 10 to 22 carbon atoms; R' is selected from the group consisting of hydrogen, an alkyl radical having 1-3 carbon atoms and a lower alkanol radical having 1-3 carbon atoms substituted with 1-3 hydroxyl groups distributed not more than 1 hydroxyl group for each carbon atom; R'' is selected from the group consisting of hydrogen, a monocarbocyclic radical having 5-6 ring carbon atoms, an alkyl radical having 1-16 carbon atoms and an alkenyl radical having 2-16 carbon atoms; X is selected from the group consisting of hydrogen and halogen, with an esterifying agent selected from the group consisting of a 10 to 22 carbon atom fatty acid, a natural resin acid and hydrogenation products thereof, a polycarboxylic organic acid and anhydrides thereof and polyhydric aliphatic alcohols.

ing an intermediate product, comprising a monomeric tetrahydrophthalic acid half ester of a monoester of a 10 to 22 carbon atom fatty acid with a polyhydric aliphatic alcohol having at least three hydroxyl groups, with an esterifying agent consisting of a polyhydric aliphatic alcohol.

8. The method of forming an alkyd resin comprising simultaneously esterifying and condensing an intermediate product, comprising a monomeric tetrahydrophthalic acid half ester of a monoester of a 10 to 22 carbon atom fatty acid with a polyhydric aliphatic alcohol having at least three hydroxyl groups, with an esterifying agent selected from the group consisting of a 10 to 22 carbon atom fatty acid, a natural resin acid and 15 hydrogenation products thereof, a polycarboxylic organic acid and anhydrides thereof and polyhydric aliphatic alcohols, by first dissolving the intermediate half ester compound and esterifying agent in proportion of 3 mols of intermediate to 20 from 1 to $\frac{1}{4}$ of a mol of esterifying agent in a volatile organic solvent capable of azeotropic distillation with water, and then azeotropically dis-

tilling said solution to remove water of condensation.

9. The method of forming an alkyd resin comprising simultaneously esterifying and condensing an intermediate product, comprising a monomeric tetrahydrophthalic acid half ester of a monoester of a 10 to 22 carbon atom fatty acid with a polyhydric aliphatic alcohol having at least three hydroxyl groups, with an esterifying agent consisting of a polycarboxylic organic acid.
